UNITED STATES PATENT OFFICE.

ROBERT TAYLOR JOHNSTON, OF SCOTCH PLAINS, NEW JERSEY.

PRINTING-PRESS.

1,069,139.

Specification of Letters Patent.

Patented Aug. 5, 1913.

Application filed December 18, 1911. Serial No. 666,354.

To all whom it may concern:

Be it known that I, ROBERT TAYLOR JOHNSTON, a citizen of the United States, residing at Scotch Plains, in the county of Union 5 and State of New Jersey, have invented certain new and useful Improvements in Printing-Presses, of which the following is a specification.

This invention relates to printing presses 10 of the bed and cylinder type and aims in general toward improvements in the construction, operation and efficiency of this type of presses and more particularly toward the provision of novel inking mechanism and means for operating the same.

One of the objects of the invention is to provide individual inking mechanisms each 20 adapted to ink a portion only of the printing form and to mount these mechanisms both on the same side of the printing cylinder in such a manner that the inking operations may be performed with a shorter stroke of the form bed than has heretofore been possible with inking mechanisms 25 mounted on one side of the cylinder.

Another object of the invention is to provide new and improved means for raising and lowering the inking rolls of the individual inking mechanisms in succession at 30 predetermined position of the printing bed, and for retaining each roll in contact with its particular portion of the printing form throughout the entire length thereof and for preventing the rolls from contacting 35 with the other portion of the form.

A further object of the invention is the provision of adjusting means carried by the form bed whereby the roll raising and lowering mechanisms may be regulated to time 40 the roll movements in conformity with the size and character of the particular printing form being used.

Additional objects and many of the advantages of the invention will be apparent 45 to those skilled in the art, as the invention becomes better understood from the following description when considered in connection with the accompanying drawings throughout the various views of which like 50 reference characters refer to similar parts.

On the drawings—Figure 1 is a fragmentary side elevation of a printing press embodying one form of my invention. Fig. 2 is a plan view thereof, certain portions of 55 the machine being removed to more clearly disclose the parts located thereunder. Fig.

3 is a longitudinal sectional view on the line 3—3 of Fig. 4. Fig. 4 is a transverse sectional view taken on the line 4—4 of Fig. 1; and Fig. 5 is a fragmentary detail view 60 showing one of the reciprocatory plates in section and the mechanism for operating the same.

From the drawings it will be observed that upon the main supporting frame 6 of the 65 machine is mounted the impression cylinder 7 and the reciprocatory form bed 8, the impression cylinder and bed being rotated and reciprocated respectively in the usual manner by any preferred driving mechanism 70 (not shown). The reciprocatory bed carries the printing form which, in accordance with the requirements of the work done on machines of this character is divided by a central margin 9 into a head portion 11 and a 75 tail portion 12, respectively. The individual portions of the printing form may be of any preferred construction although customarily they are made up of a number of individual sections each provided with suitable printing 80 characters or surfaces.

In order to reduce the length of stroke of the bed, thereby reducing the size of the impression cylinder and other machine parts and increasing the output of the machine 1 85 mount and operate the inking rolls in such a manner that the entire form is completely and uniformly inked without passing the full length of the form under all the inking rolls as has been customary heretofore in 90 the operation of machines in which the inking rolls are all located at one side of the cylinder. To this end I have divided the inking rolls into sets each adapted to ink a portion of the form, the set 13 nearest the 95 impression cylinder, and hereafter referred to as the head mechanism, being designed to ink the head portion 11 of the form and the other set 14 more remote from the impression cylinder and hereafter referred to 100 as the tail mechanism being adapted to ink the tail portion 12 of the form. The head mechanism comprises the inking rolls 15 and 16 normally contacting with the distributing roll 17 which is driven from the rack 18, 105 carried by the form bed, through the intermediary of a gear 19. The tail mechanism comprises the inking rolls 22 normally contacting with the distributing roll 23 which, in turn, is also rotated from the rack 18 110 through the intermediary of the gear wheel 24. The distributing rolls 17 and 23 are

mounted in stationary sockets in the usual manner but the inking rolls are each mounted in movable sockets whereby the rolls may be raised to prevent contact with one portion of the form and lowered to contact with and ink the other portion.

For the purpose of raising and lowering the individual inking rolls in succession as the bed travels back and forth beneath the impression cylinder I have mounted cam members 25 and 26 upon opposite sides of the reciprocating bed and provided operative connections between the cam members and the inking rolls whereby the rolls are raised and lowered at predetermined positions of the bed. The cam members are secured to the side members of the bed by means of bolts 27, said side members being provided with elongated slots 28 permitting adjustment of the members longitudinally of the bed. Each cam member is provided with an upper cam slot 29 and a lower cam slot 31, comprising relatively long dwell portions extending in both directions from the riser portions 32 and 33, respectively. In suitable bearings upon each side of the frame I have mounted a series of short shafts 34, 35, 36 and 37, upon the inner ends of which are fixed the arms 38, 39, 41 and 42 respectively carrying at their outer extremities the cam followers or pins 43, 44, 45 and 46. The followers 43 and 46 travel in the cam slots 29 while the followers 44 and 45 travel in the cam slots 31. It will be evident that as the cam members are reciprocated with the bed the shafts 34 and 37 will be successively oscillated by the riser portion of the cam 32 and that the shafts 35 and 36 will be likewise oscillated in the opposite direction by the riser portion 33 of the cam slot 31. Suitable mechanism is provided to transmit the oscillatory movements of these shafts into right line movements for raising and lowering the inking rolls.

The inking rolls are mounted at each end in sockets 47 opening radially of the distributing rolls 17 and 23, respectively, so that said distributing rolls hold the inking rolls in position in their sockets but permit the inking rolls to be lifted out of their sockets upon removal of the distributers. The sockets are mounted so as to be capable of vertical adjustment in socket members 48 adjustable horizontally on the reciprocatory carrying plates 49. The sockets are preferably held in adjusted position in the socket members by set-screws 51 while the socket members, in turn, are retained in adjusted position on the carrying plates by the slot and bolt connections 52. It will be evident that the distance of the inking rolls from the printing form can be regulated by adjusting the sockets upwardly and downwardly in their holders and that the rolls can be adjusted toward and from their re-

spective distributers by horizontal movement of the socket holders on the carrying plates. Each carrying plate is set in a depression 53 in the side of the machine frame and held in position therein by securing bolts 54, as shown in Figs. 1 and 5. The depressions 53 are inclined to the vertical so that as the plates are moved back and forth therein the inking rolls of each set are moved apart and elevated on lines tangent to the peripheries of their respective distributers. The oscillatory movements of shafts 34, 35, 36 and 37 are transmitted to their respective plates 49 through gear segments 55 mounted on the outer ends of the shafts and meshing with rack teeth 56 formed on the lower edges of the carrying plates 49.

The operation of the mechanism thus far described is as follows: Assuming that the parts are in the position shown in Fig. 1 and that the form bed is traveling toward the right: The cam followers 43, 44, 45 and 46 are each in contact with the low or central portions of the cam slots and by reason of the adjustment of the various parts the inking rolls of the head mechanism 13 are in elevated position while the rolls of the tail mechanism 14 are in lowered or operative position. As the printing form continues to move toward the right the tail portion 12 thereof will contact with the inking rolls 21 and 22, the circumference of each being preferably greater than the maximum of the tail portion of the form so that fresh roll surfaces are presented by each roll to every part of the form portion as it travels under the rolls. A uniform and even distribution of ink over the tail portion will, therefore, be effected by the inking mechanism 14 as the tail portion travels thereunder. The inking rolls of the head mechanism 13 being in the meantime retained in elevated position until the tail portion of the form passes out from under them. When the central margin 9 separating the head and tail portions 11 and 12 reaches a position under the inking roll 15 the risers 32 of the cam slots 29 on each side of the machine are brought into engagement with their respective followers 43 which are elevated thereby to oscillate the shafts 34 thereby drawing down the carrying plates 49 and lowering the roll 15 into operative relation with the head portion of the form. When the margin 9 reaches the roll 16 this roll is similarly lowered by engagement of the cam followers 44 with the riser portions 33 of the cam slots 31. As the form continues to travel toward the end of the machine the tail portion will travel out from under the roll 21 of the tail mechanism whereupon said roll will be elevated at the margin 9 by the cam risers 33 which, through the cam followers 45, oscillate the shafts 36, similarly the roll 22 is elevated at the mar-

gin 9 through the shafts 37 which are oscillated by their respective followers 46 as the risers 32 engage therewith. When the bed has traveled a sufficient distance to pass the 5 head portion of the form entirely under both rolls 15 and 16, reversal of the bed takes place. It will thus be obvious that the travel of the bed is materially reduced over the travel in those machines so constructed that the entire printing form must 10 be passed under all of the inking rolls of the entire inking mechanism. Upon reversal of the bed the rolls of the head mechanism are successively raised as the head portion 15 of the form travels out from under them and the rolls of the tail mechanism are successively lowered into engagement with the tail portion as the head portion is withdrawn 20 from under them. Thus it will be seen that the individual inking rolls of both the head and tail inking mechanisms are successively raised and lowered as the bed reciprocates to maintain contact between the rolls and their respective portions of the form and 25 prevent contact with the other portion of the form.

Since the position of the head line of all forms employed remains fixed relatively to a predetermined point on the periphery of 30 the impression cylinder, it will be manifest that the position of the central margin 9 will necessarily vary in forms of different sizes. In order that the cam members may be simultaneously adjusted on the bed to 35 correspond with the position of the central margin and thereby insure the proper timing of the raising and lowering movements of the inking rolls, I have provided a cross adjusting shaft 57 mounted on the bed of 40 the machine and provided at its ends with gear wheels 58 and 59, meshing with racks 61 and 62 respectively formed on the cam members 25 and 26. By rotating this shaft the cam members may be adjusted simultaneously and in unison longitudinally of 45 the bed to bring the riser portions of the cams into proper position relatively to the central margin of any form being used. A set-screw 63 threaded through one of the 50 bearings of the shaft 57 is adapted to lock the shaft against rotation after the cam members have been adjusted to the required position and one end of the shaft 57 is preferably squared as shown at 64 to receive a handle by which the adjusting movements may be effected. 55

It is believed that my invention and many of its attendant advantages will be understood from the foregoing without further 60 description and, while I have shown and described that practical embodiment of my invention which at the present time seems to be preferable, it will be obvious that various mechanical changes in the construction of 65 the various parts may be resorted to without

departing from the spirit of the invention or sacrificing any of the material advantages thereof.

I claim:

1. In a printing press, the combination of 70 a reciprocatory bed, a plurality of inking rolls, independent mechanisms at each side of the bed adapted to simultaneously elevate both ends of the rolls, and means mounted on the bed and connected to simultaneously 75 adjust said mechanisms whereby the raising of the rolls may be hastened or retarded relatively to a predetermined position of the bed.

2. In a printing press, the combination of 80 a reciprocatory bed, cam mechanism carried by said bed, a plurality of inking rolls, means adapted to be operated by said cam mechanism for raising and lowering said rolls at predetermined positions of the bed, 85 and a single adjusting means mounted on the bed whereby the cam mechanism may be adjusted to hasten or retard the raising and lowering movements of all of the rolls.

3. In a printing press, the combination of 90 a reciprocatory bed, a cam mounted on each side of said bed, an inking roll, a plurality of plates upon which said inking roll is mounted, operative connections between said plates and said cams whereby the roll is raised and lowered upon reciprocation of the bed, and means mounted on the bed for simultaneously adjusting the position of said cams to hasten or retard the raising and lowering movements of said roll. 95

4. In a printing press, the combination of 100 a reciprocatory bed, cams carried on each side of the bed, a plurality of inking rolls, raising and lowering mechanism connected with each of said rolls and adapted to be operated by said cams to raise and lower said rolls in succession at predetermined positions of the bed, and an adjusting mechanism carried on the bed whereby the cams may be synchronously adjusted to hasten or 110 retard said raising and lowering movements of the rolls.

5. In a printing press, the combination of 115 a reciprocatory bed, cams adjustably mounted on each side of the bed, inking rolls, reciprocatory plates upon which said rolls are mounted, means including a rack and pinion for operatively connecting said plates with said cams whereby the rolls are raised and lowered from the cams at predetermined positions of the bed, and adjusting mechanism whereby the position of the cams on the bed may be varied to hasten or retard the times at which the rolls are raised and lowered. 120

6. In a printing press, the combination of 125 the main frame of the machine, a reciprocatory bed, a pair of cam members adjustably connected with said bed, a plurality of inking rolls, a pair of plates for each roll, sockets mounted on said plates and support- 130

ing the rolls, oscillatory members mounted on the frame and connected with said plates for imparting a right line movement thereto, cam followers fixed on said oscillatory devices and adapted to be actuated by said cam members for imparting right line raising and lowering movements to said rolls in succession upon reciprocation of the bed, and mechanism connected with both of said cams whereby the cams may be adjusted and maintained in predetermined relation.

7. In a printing press, the combination of a reciprocating bed, cam members adjustably mounted thereon to reciprocate there-

with, inking rolls, mechanism adapted to be operated from said cam members to raise and lower said rolls in succession upon reciprocation of the bed, racks formed on said cam members, an adjusting shaft extending transversely of the machine, and pinions on said shaft meshing with said racks whereby upon rotation of the shaft said cam members may be adjusted longitudinally of the bed.
